UNITED STATES PATENT OFFICE.

ALBERT A. GORDON, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

LAY FOR LOOMS.

Application filed November 6, 1924. Serial No. 748,279.

This invention relates to improvements in lays for looms and more particularly to the construction and adjustment of the lay swords on which the lay is mounted.

5 The form of lay sword shown in Patent No. 1,377,834 issued to Holmes employs a pipe the ends of which are threaded oppositely, the upper end having attachment with a casting secured to the lay and the lower end being received by a bearing connected to the rocker pin. The pipe as shown in the aforesaid patent is straight with the threaded ends in alignment. Such a construction has heretofore been employed in
10 10 connection with the so-called spindle pick which requires that the picker stick be disposed rearwardly of the shuttle. The constant vibration of the lay has a tendency to loosen the ends of the sword, permitting
15 15 it to rotate because of the alignment of the ends. When the picker stick is located in a slot formed in the lay so as to be in line with the shuttle it is found to be far enough forward so that the power arm and connections will interfere with the straight lay sword. To overcome this objection I have offset the sword to provide room for the picking connections, and in doing so it has been necessary to locate the sword ends out
20 20 of alignment, with the result that the objectionable turning of the sword is prevented. It is the general object of my present invention to improve the construction of pipe lay swords to prevent rotation
25 25 thereof and permit the same to be used with a picker stick movable in a slot of the lay.

It is a further object of my invention to provide means for adjusting the lay sword without requiring the latter to be rotated,
30 30 the adjustment being accomplished by connections which enable the parts to retain any given setting.

With these and other objects in view which will appear as the description proceeds, my invention resides in the combination and arrangement of parts hereinafter described and set forth in the claims.

In the accompanying drawings wherein I have shown one form of my invention,
35 35 Fig. 1 is an end elevation of a portion of a loom having my invention applied thereto, part of the lay being shown in section,

Fig. 2 is a front elevation of the construction shown in Fig. 1,

Fig. 3 is a vertical section on line 3—3 of Fig. 2,

Fig. 4 is a horizontal section on line 4—4 of Fig. 3, and

Fig. 5 is a section on line 5—5 of Fig. 3. Referring more particularly to Figs. 1 and 2 it will be seen that I have provided a loom side 10 having a breast beam 11 and rocker pin 12 mounted on bearing block 13 secured to the loom side. The lay 14 is slotted as at 15 and is driven by means of connector 16. The picker stick 17 is pivoted as at 18 to the picker foot 19 and is actuated by lug strap 20 which is connected to power stick 21 the inner end of which is attached to and actuated by picker arm 22. Said arm receives a periodic inward motion to rock the picker stick about the pivot 18 and cause the upper end of said picker stick to move into slot 15 to propel the shuttle S. These parts may be of the usual and well known construction.

In carrying out my invention I provide a foot 30 which is secured to the rocker pin 12 by means of set screws 31. That portion of the foot 30 opposite the rocker pin is split as at 32, shown more particularly in Fig. 4, and the split parts are held together by a bolt 33 having a head 34 on one end and a nut 35 on the other end.

The foot is provided with a bore 36 which receives a sleeve 37 slightly shorter than the bore 36 and having a head 38 on the upper end thereof and having a longitudinal slot 39 cut therein to render the same slightly resilient and compressible. The inner wall of the sleeve 37 is threaded as at 40 to receive the lower threaded end 41 of a pipe 42. A nut 43 is threaded in the lower end of the pipe 42 and lies on that side of the foot opposite the head 38. A wooden block 44 may be driven into the lower end of the pipe in order to stiffen the same.

As shown in Fig. 1 the pipe 42 is provided with a central offset 45 which extends forwardly of the power stick 21 and affords sufficient room for the latter in all positions of the lay.

The upper end of the pipe is provided with a threaded portion 46 received in a split bearing 47 secured to the lay 14. A bolt 48 serves to retain the setting of the split bearing 47.

It will be understood that when the lay

sword is provided with the offset 45 it will be impossible to secure all of the adjustment of said sword by a rotation of the parts thereof inasmuch as some adjustments might move said portion 45 directly into the path of the power stick 21.

When setting the lay sword the bolt 33 will be loose and the split sleeve 37 expanded. The sleeve 37 may then be turned to raise or lower the same as conditions require until the proper setting of the adjacent end of the lay is obtained after which the nut 43 may be turned to move the same against the bottom of the foot 30. In order to turn the head 38 the latter may be provided with holes 49 arranged to receive the end of a spanner wrench. After the nut 43 has been drawn against the foot 30 bolt 33 may be tightened, thus causing a slight compression of the sleeve 37 which will serve further to bind the several parts together. It will be seen that compression of the split sleeve 37 serves to hold the nut 43 and head 38 against foot 30 and binds the internal threads 40 thereof against the threads 41 so that all the parts are securely held together by the bolt 33. It is to be understood that I may use a sword such as herein described at each end of the lay, although where drop shuttle boxes are used, the straight type of sword may be used.

By referring to the drawings it will be seen that the ends of the sword are not only out of alignment but are also angularly disposed with respect to each other. Because of this arrangement any tendency on the part of one end of the sword to rotate is counteracted by the opposite end, and even though both ends should become loose, the sword would be held against rotation and consequent loss of adjustment because of the relation of the ends of the sword.

From the foregoing it will be seen that I have provided a lay sword formed of hollow tubular construction so arranged as to permit fine adjustment thereof in such a way that the adjustment may be held securely. Also, when the nut 43 is loosened the head 38 supports the lay so that the reed will not fall to damage the warps and when the adjustment is made by the sleeve, it is not disturbed by tightening the nut 43.

Having thus described my invention it will be apparent that changes and modifications may be made therein by those skilled in the art without departing from the spirit and scope of the invention and I do not wish to be limited to the details herein disclosed, but what I claim is:

60 1. In a loom, a lay, a sword connected at one end thereto, a supporting foot for the other end of the sword, and a sleeve located between the sword and the foot, said sword extending through the sleeve and said sleeve and sword having cooperating threaded por-

tions to adjust the sleeve and sword relatively, said sleeve having a shoulder to engage the foot and limit motion of said sleeve and sword relatively to the foot.

65 2. In a loom, a lay, a sword connected at one end thereto having the lower end thereof threaded, a supporting foot for the other end of the sword, and a rotatable member between the foot and sword and threaded on the latter to be movable longitudinally with respect to said sword, said member having a part thereof in engagement with the foot to prevent motion of said member with respect to the foot.

70 3. In a loom, a lay, a sword connected at one end thereto, a supporting foot for the other end of the sword, a sleeve located between the sword and foot, said sleeve and sword having cooperating threaded portions by which to adjust the relative position of said sleeve and sword, said sleeve being split longitudinally, and means to compress said split sleeve to secure close contact between the threaded portions of the sleeve and sword.

75 4. In a loom, a lay, a sword connected at one end thereto, a supporting foot for the other end of the sword, a sleeve located between the sword and foot, said sleeve and sword having cooperating threaded portions by which to adjust the relative position of said sleeve and sword, said sleeve being split longitudinally, means to compress said split sleeve to secure close contact between the threaded portions of the sleeve and sword, and means to prevent relative movement of the sleeve with respect to the foot.

80 5. In a loom, a rocker shaft, a bearing member fastened to the shaft, a sleeve mounted in an open bearing formed in the member, said sleeve and bearing member both being split, a lay sword having the lower end thereof threaded, the sleeve being provided with an internally threaded bore to receive the lower end of the sword, a shoulder on the sleeve in engagement with the bearing, a threaded locking device on the sword movable into contact with the bearing member on the side thereof opposite the shoulder, and means to clamp the split bearing of the bearing member against the split sleeve.

85 6. In a loom, a rocker shaft, a lay sword having the lower end thereof threaded, and an adjustable connection between the rocker shaft and the lay sword, said connection comprising a split bearing member fastened to the rocker shaft, a split sleeve received in the split bearing and having an internally threaded bore to cooperate with the threaded end of the lay sword, said sleeve having a shoulder on one side of the split bearing, a locking member threaded and mounted on the threaded portion of the sword and movable into contact with that

portion of the bearing opposite the shoulder, and means to clamp the split portion of the bearing against said split sleeve.

7. In a loom, a lay sword having the lower portion threaded, a rocker shaft, a bearing member fastened thereon, a sleeve member having a threaded connection with the lower portion of the sword, one of said members being received by the other member and both 10 of said members being split, and a single clamping means to clamp both of said split members together and to clamp the sleeve against the threaded portion of the sword.

8. In a loom, a lay, a sword connected at 15 the upper end thereto and having the lower end thereof threaded, a supporting foot for the sword, and a rotatable member between the foot and sword and threaded on the latter to be movable longitudinally with respect to said sword, and means associated 20 with the member to engage a part of the foot and prevent motion of said member relatively to said foot.

9. In a loom, a lay, a sword connected at 25 the upper end thereto, a bearing for the sword, the lower end of the sword extending through the bearing, a sleeve located in the bearing and normally held against relative longitudinal movement with respect 30 thereto and surrounding the lower portion

of the sword, and means to prevent relative longitudinal movement of the sleeve and lower end of the sword.

10. In a loom, a lay, a sword connected at the upper end thereto, a bearing for the 35 sword, a hollow rotatable member located in the bearing and normally held against relative longitudinal movement with respect to the bearing, the lower end of the sword passing through the rotatable member, and 40 means to afford relative adjustment of the sword with respect to the bearing when the hollow rotatable member is rotated.

11. In a loom, a lay, a sword connected at the upper end thereto, a rocker shaft, a 45 bearing for the sword mounted on the shaft, a sleeve rotatably mounted in the bearing and lying on one side of the shaft, the lower end of the sword extending entirely through the sleeve and bearing, said sleeve being normally held against longitudinal movement in the bearing, and threaded connections between the sleeve and the sword whereby rotary movement of the sleeve effects relative movement of the sword with respect to 50 the bearing.

In testimony whereof I have hereunto affixed my signature.

ALBERT A. GORDON,
